UNITED STATES PATENT OFFICE

WALTER A. BOHN, OF LAKEWOOD, OHIO, ASSIGNOR TO MASTER PRODUCTS COMPANY,
OF CLEVELAND, OHIO, A CORPORATION OF OHIO

DESIGN FOR A CASING FOR A BEARING

Application filed September 15, 1932. Serial No. 44,857. Term of patent 14 years.

To all whom it may concern:

Be it known that I, WALTER A. BOHN, a citizen of the United States, residing at Lakewood, in the county of Cuyahoga and State of Ohio, have invented a new, original, and ornamental Design for a Casing for a Bearing, of which the following is a specification, reference being had to the accompanying drawing, forming a part thereof.

In the drawing, Fig. 1 is a front view of a casing for a bearing embodying my design; Fig. 2 is a rear view, and Fig. 3 is an end view of the casing.

I claim:

The ornamental design for a casing for a bearing substantially as shown.

WALTER A. BOHN.
